UNITED STATES PATENT OFFICE.

CHARLES E. MAIER, OF CAMBRIDGE, OHIO, ASSIGNOR TO THE OXFORD POTTERY COMPANY, OF CAMBRIDGE, OHIO, A CORPORATION OF OHIO.

DESIGN FOR A COVERED DISH.

49,544.

Specification for Design.

Patented Aug. 22, 1916.

Application filed February 25, 1916. Serial No. 80,529. Term of patent 3½ years.

To all whom it may concern:

Be it known that I, CHARLES E. MAIER, a citizen of the United States, residing at Cambridge, in the county of Guernsey and State of Ohio, have invented a new, original, and ornamental Design for a Covered Dish, of which the following is a specification, reference being had to the accompanying drawing, forming part thereof.

Figure 1 is a top plan view of a covered dish embodying my design, and Fig. 2 is a side elevation thereof, partly in section.

I claim:

The ornamental design for a covered dish, as shown.

CHARLES E. MAIER.
